 Pressed Steel Car Company, Inc., Pittsburgh,
 Pa., a corporation of Pennsylvania

Application March 8, 1937, Serial No. 129,657
 Renewed September 29, 1939

21 Claims. (Cl. 105—272)

Dump vehicles of the character hereinafter described have the body thereof provided with opposite side walls formed of doors hinged adjacent the floor of the body and opening outwardly to discharge lading. The body when in normal position is supported in stable equilibrium on laterally spaced bearing surfaces of the underframe and moves to dump position on bearing surfaces spaced outwardly of the supports for the body in stable equilibrium. A mechanism for controlling each door is mounted on the body and is actuated by relative movement between the body and underframe. The door controlling mechanism must hold the doors in closed position when the body is in normal position and selectively release the door for opening at the dumping side only as the body tilts upon the underframe. The door operating mechanism is therefore entirely automatic and controlled by the body in its various positions relative to the underframe. Some means must be provided for actuating the body, but such means forms no part of the present invention and any one of a number of suitable body tilting means well known in the art may be used.

The dump vehicles herein described handle a variety of lading and are exposed to all kinds of weather conditions so that there are times when the door at the discharging side of the body adheres to the lading and is prevented from opening as the body is tilted. At other times, previously discharged lading or other obstructions at the side of the vehicle will engage the door after same has begun its opening movement upon tilting of the body and will prevent further downward movement of the door. For these reasons it becomes necessary to provide means whereby the door control mechanism does not positively actuate the door in its opening movements and the herein described invention exercises positive control of the closing movement but not the opening movement of the door. It is necessary, however, to provide some control of the opening door, otherwise the door dropping freely upon tilting of the body and under the weight of the discharging lading would be damaged upon abruptly striking the vehicle or other means provided to limit the opening of the door. For this reason the present invention limits the rate of opening of the door by the rate of tilting of the body. This restraint upon the door is utilized to assist in tilting the body and therefore reduce the necessary size of body tilting mechanism.

This invention pertains generally to dump vehicles having a tilting body and the side walls of the body formed of doors hinged adjacent the

floor thereof and opening outwardly and downwardly as the body is tilted. The invention pertains specifically to mechanism mounted on the body and engaging the underframe to control the opening and closing movements of the doors by 5 the relative positions of the body and underframe.

An object of the invention is to provide a door controlling mechanism which will maintain the doors locked in closed position when the body is 10 horizontal, which will limit the opening and positively close the doors as the body moves relative to the underframe in its dumping and righting movements.

Another object of the invention is to provide a 15 door controlling mechanism which will maintain the doors on the rising side of the body closed when the body is tilted for dumping.

A further object of the invention is the provision of a door mechanism which positively 20 moves the door from open to closed position and releases the door for moving from closed to open position solely by gravity and permits closing of the door independently of the tilting movement of the body.

In the drawings forming part of this specification, Fig. 1 is a transverse vertical section through a railroad car equipped with one form of the invention and having the body in normal position; Fig. 2 is a section similar to that shown in Fig. 1 30 with the body in fully tilted position; Figs. 3 and 4 are transverse vertical sections through the car showing modifications of the invention; Figs. 5 and 6 are sections taken on the lines 5—5 and 6—6 of Fig. 1; Figs. 7 and 8 are sections taken on 35 the lines 7—7 and 8—8 of Figs. 3 and 4 respectively.

Referring now in detail to the drawings where like reference characters refer to like parts, reference character 1 indicates generally a railroad 40 dump car having an underframe comprising a center sill structure 2 with laterally disposed members 3 secured on opposite sides of the center sill structure. On the upper face of some of the members 3 are bearing surfaces 4 supporting the 45 car body in normal position and concave bearing surfaces 5 spaced outwardly therefrom for supporting the body whilst tilting about the underframe. It is to be understood that if desired the body supporting bearings can be designed so as 50 to engage but one bearing surface on either of the members 3, both for supporting the body during normal position and during tilting.

Supported on the underframe by means of 55 bearings 6 is a tiltable body comprising trans-

verse stiffening members 7 having a floor 8 disposed thereon with fixed end walls 9 at opposite ends of the car and side walls 10 formed of doors hingably mounted at 11 on bearings secured to the members 7. Each door has connected therewith and disposed beneath the floor of the body a plurality of door controlling members pivotally mounted on bearing plates 12 secured to the body adjacent their respective door and pivotally connected with a downward extension 13 of the door. These door mechanisms are disposed on opposite sides of the underframe center sill structure 2 and the adjacent opposite mechanisms are connected by means of the link 14.

15 Each door controlling mechanism comprises a bifurcated link 15 pivotally mounted on a shaft 16 journaled in the bearing plates 12 and having a member 17 mounted on the shaft 16 within the bifurcation of the link 15. The outer end of the link 15 is pivotally connected to a lever 18 by means of the pin 19, said outer link 18 having its outer end pivotally connected to the door extension 13 by means of the pin 20. Said lever 18 comprises an outer portion 18^a pivotally mounted on the door extension 13 and an inner portion 18^b with a threaded joint between the portions 18^a and 18^b to provide adjustment in the linkage formed of the links 15 and lever 18. Pivotally mounted on a shaft 21 journaled on the inner end of the lever 18 is a roller 22 engaging the upper face of the member 17 for the purpose of controlling movement of the links 15 and lever 18. The shaft 16 on which the cam 17 is pivotally mounted is disposed below the upper surface of the center sill structure 2 and the cam 17 extends above the upper plane of the center sill structure and has a lug 23 on its upper face pivotally connected to the link 14 by means of the pin 24. Secured to the center sill structure 2 and extending thereabove and adjacent each side thereof is a bracket 25 having a shaft 26 journaled therein upon which is a roller 27 adapted to engage the adjacent cam 17 of the adjacent door mechanism.

45 Referring now to Fig. 1 of the drawings it will be obvious that with the body in normal position, the doors 10 forming the side walls of the body tend to rotate outwardly of the body by reason of the forces of gravity and the lading within the body acting upon both doors, and that the connection 15-18 between the door and the adjacent side of the body can only break upwardly by reason of the joint 19 being above a straight line drawn through the pins 16 and 20 at the ends of 50 the jointed link. This upward movement of the connection 15-18 between the door and body is resisted by the roller 22 of the lever 18 engaging the cam 17.

When the body is tilted about the right side of 60 the underframe and moves from the position shown in Fig. 1 to that shown in Fig. 2, the body pivots on the bearing 6 engaging the bearing surface 5 of the underframe and the door tends to rotate downwardly on its hinge pin 11 which rotation is resisted by roller 22 of link 18 engaging cam 17. This pivotal movement of the body tends to raise the cam 17 at the right side of the body above the roller 27 on the adjacent side of the underframe, thereby permitting the cam 17 to rotate inwardly of the body upon the shaft 16. This rotation of the cam 17 raises the curved portion of the cam above the roller 22 on the lever 18, permitting the jointed connection 15-18 to break upwardly and the door to open. It will be obvious that the descending door 10 on the right

side of the body could not impart any movement to the cam 17 associated with that door. This requisite movement of the cam 17 is provided by means of the link 14 and the cam 17 on the opposite side of the body, it being noted that as the body rotates about the bearing 6 on the right side of the body, the cam 17 on the left side of the body is forced into engagement with the roller 27 on the left side of the underframe, causing the cam 17 on the left side of the underframe to rotate toward its associated door and this movement is transmitted to the cam 17 on the opposite side of the body by means of the link 14. This movement of the cam 17 on the left or rising side of the body maintains that cam in position to hold its associated door locked in closed position whilst the left side of the body is out of engagement with the underframe.

From the above description it will be obvious that the sole forces acting to open the door at the dumping side of the body were the forces of gravity and the weight of lading against the door. The face of cam 17 engaged by roller 22 is so formed that cam 17 can be rotated relative to roller 22 without necessity for movement of link 15 and lever 18, but lever 18 cannot move upwardly relative to cam 17 without prior movement of cam 17 because of the relative positions of link 15, roller 22 and face of cam 17. Therefore, if for any reason the door does not open upon tilting of the body, the door or mechanism will not be damaged by continued tilting of the body, and if after partially opening the door strikes an obstruction, the door can move to closed position independently of continued tilting of the body. Likewise, it is also apparent that inasmuch as the cam 17 must move above roller 22 before the door can open and upon opening of the door roller 22 engages the lower face of cam 17, the rate at which the door can open is limited to the rate at which the tilting body moves the back face of cam 17 relative to roller 27 at the adjacent side of the underframe to permit rotation of cam 17.

Upon return of the body from position shown by Fig. 2 to that shown by Fig. 1, the body in forcing cam 17 against roller 27 causes cam 17 to rotate toward the adjacent door. This movement of cam 17 places lever 18 in compression and causes the open door to rotate into closed position as the body comes to rest upon the underframe. At the left or upper side of the body the cam 17 and link 18, attached to the door on the left side of the body, do not change position relative to each other, thereby retaining their associated door in closed position until the body returns to normal position. Whilst it is true that there is some relative movement between cam 17 and roller 22 associated with the door at the left side of the body at the beginning of the tilting and at the end of the righting movements of the body, the movement is insufficient to release roller 22 from the curved face of cam 17 and therefore the door cannot open.

It will be obvious that when the body is tilted about the left side of the underframe and about the bearings 6 on that side of the body, the operation of the door mechanism will be similar to that described supra excepting that the mechanism on the left side of the body will now become the active mechanism to control the opening and closing of the door and the mechanism on the right side of the body will remain inactive to maintain the door on the rising side of the body.

closed during the dumping and righting movements.

Referring now to Figs. 3 and 7 of the drawings, all of the elements forming the body and underframe are the same as shown in Fig. 1 and likewise are the link 15 and lever 18 pivotally connecting the door extension 13 to the pin 16 of the body. The cam member 117 is different than in the previous disclosure and is shown as being normally in engagement with the roller 121 mounted on the center sill structure. When the body tilts about the opposite side of the underframe the roller 121 will again impart movement to the cam 117 as previously described for cam 17. At the dumping side of the body the same relative movements between link 15, lever 18 and cam 17 take place as was previously described in connection with link 15, lever 18 and cam 17.

In Figs. 4 and 8 of the drawings is shown a further modification of the invention, all of the portions of the door mechanism, the body and the underframe being the same as in Fig. 1 excepting that the cam member 217 has a roller 28 mounted thereon and engaging a stop 29 mounted on the center sill structure 2 for the purpose of imparting movement to the cam 217 when the body tilts about the opposite side of the underframe. At the dumping side of the body roller 28 of cam 217 moves about stop 29 on the underframe to effect the same control of cam 217, link 15 and lever 18 as was previously described in connection with cam 17, link 15 and lever 18 of Figs. 1 and 2.

Having thus described the invention, what I desire to secure by Letters Patent is:

1. In a dump vehicle provided with an underframe and a tilting body having opposite side walls hinged adjacent the floor thereof, the combination of a link on the body adjacent each door, a lever connecting said link and adjacent door, a cam shaped member on the body adjacent each link and means operably connecting said cam shaped members and vehicle underframe to selectively actuate each cam shaped member by relative movement between the body and underframe to dispose the cam in the path of movement of the adjacent link and lever connection between the body and door for controlling the opening and closing movements of the door as the body moves in dumping about the adjacent side of the underframe.

2. In a dump vehicle in combination, an underframe, a body supported thereon and tiltable toward a side thereof, a door forming a side wall of the body and hinged adjacent the floor thereof for opening outward and downward as the body is tilted, a link and lever connection between said door and body and disposed below the plane of the floor of the body, a cam on the body adjacent said link and lever connection, means on said connection engaging a face of said cam for maintaining the door in closed position when the body is in normal position, and means operably connecting said cam and underframe to control the opening and force the closing of the open door as the body moves the cam relative to the underframe during the tilting and righting movements of the body.

3. The combination in a dump vehicle of an underframe, a body supported thereon for tilting to opposite sides thereof, doors forming side walls of the body and hinged adjacent the floor thereof, a mechanism for each door comprising a link and lever connection between the door and the adjacent side of the body, a cam shaped mem-

ber associated with each link and operably engaging said lever for normally preventing relative rotation between the link and body, a link connection between opposite cam shaped members, and a bearing for each cam shaped member upon the underframe adapted to engage said cam shaped member upon tilting of the body for actuating the said cam shaped members by relative movement between the body and underframe.

4. In a dump vehicle of the character described, in combination, an underframe, a tiltable body, opposite side walls for the body comprising doors hinged adjacent the floor of the body, an arm on each door depending below said hinge connection, a link on the body below the floor thereof and adjacent each side of the body, a lever connected to said door arm, a pivotal connection between said link and lever disposed above a straight line through the connections between the link and lever to the body and door, respectively, a cam including angularly disposed faces pivoted to the body adjacent each link, one face of the cam normally engaging said lever for preventing upward rotation of said link to maintain the associated door in closed position, a link connecting said cams on opposite sides of the body and an abutment for each cam mounted on the underframe inwardly and above the connection between the adjacent cam and body for engagement during tilting of the body to selectively control movement of the cam out of normal position at the dumping side of the body.

5. In a dump car in combination, an underframe, a body tiltably mounted thereon and provided with side walls comprised of doors hinged adjacent the floor of the body for gravitational opening, means for selectively tilting the body to opposite sides of the underframe, a mechanism for each door mounted on the body adjacent the door and selectively engaging the underframe for automatic control of the adjacent door during all positions of the body relative to the underframe and a connection between opposite door mechanisms whereby the mechanism at one side of the body imparts a preliminary movement to the mechanism at the dumping side of the body during the initial tilting movements of the body and independently of movement of the associated door.

6. In a dump vehicle, in combination, an underframe having a central portion and laterally extending side portions, a body supported on and tiltable about said underframe side portions, side doors for said body hinged adjacent the floor thereof, a mechanism for each door disposed between the door and said underframe central portion and mounted on the body below the plane of said central portion, a pivoted cam member included in each mechanism, a compression member for each door and disposed between the adjacent cam member and associated door, each cam member being movable relative to said compression member and underframe and actuated by engagement with the underframe during righting of the tilted body to effect the closing of the open door through pressure exerted upon said compression member.

7. The combination in a dump vehicle of the character described, of an underframe, a body tiltably supported thereon and provided with a downwardly opening door, an arm on said door depending below the body, a jointed compression member connected with said door arm and with the body, and a cam pivoted to the body so as to be disposed between and engaged by said

jointed member and the underframe to limit the opening and force the closing of the door as the body moves in dumping.

8. In a dump vehicle in combination, an underframe, a body supported thereon and tiltable towards a side thereof for dumping, a door forming a side wall of the body and hinged adjacent the floor thereof to open outward and downward when the body is tilted, said door having a portion depending below the said hinge connection to the body, a link pivoted to and beneath the body inwardly of said door, a lever connecting said link and depending door portion, and means mounted on the body engaging the lever and underframe to lock the door in closed position when the body is in normal position and to move the door from open to closed position when the body is returned from tilted to normal position.

9. In a dump vehicle, an underframe, a body, a door forming a side wall of the body and hinged adjacent the floor thereof, a bearing on the body adjacent said door for engagement with the underframe to maintain the body in stable equilibrium when in normal position and about which the body tilts in dumping, a link on the body inwardly of the door, a lever connecting the link and door, means pivoted beneath the body and normally engaging the underframe and lever to maintain the door in closed position when the body is in normal position, said means moving relative to the underframe as the body moves in dumping to release said lever to permit the door to open by gravity and acting on said lever to force the closing of the door when the body is returned to normal position.

10. In a dump vehicle in combination, an underframe, a body having a door forming a side wall of the body and hinged adjacent the floor thereof, laterally spaced supports between the body and the underframe to maintain the body in stable equilibrium when in normal position, said support adjacent the door providing for tilting of the body during dumping, a link pivoted beneath the body inwardly of the door, a lever connecting said link and door, a cam shaped member pivoted beneath the body and normally disposed between said lever and underframe to maintain the door in closed position, said cam moving with the body relative to the underframe during dumping to release the door for opening by gravity and rotated through movement relative to the underframe and in engagement therewith during return of the body to normal position to actuate said lever to force the return of the open door to closed position during the return movement of the body.

11. In a dump vehicle in combination, an underframe, a body, doors forming opposite side walls of the body and hinged adjacent the floor thereof, laterally disposed bearing supports secured beneath the body and engaging the underframe to maintain the body in stable equilibrium when in normal position, said body selectively tilting about said supports during dumping to the opposite sides of the underframe, a link pivoted beneath the body adjacent each door and inwardly of the adjacent support for the body when in tilted position, a lever connecting each link and the adjacent door, a cam shaped member pivotally mounted beneath the body adjacent each link and normally disposed between the adjacent lever and underframe to maintain the associated door in closed position, said cam associated with the descending door moving with the body relative to the adjacent side of the un-

derframe during dumping to release the door for opening by gravity and rotated through movement relative to the underframe and in engagement therewith during return of the body to normal position to actuate said lever to force the return of the open door to closed position during the return movement of the body.

12. In a dump vehicle, having an underframe, a body tiltable selectively towards opposite sides of the underframe, doors hinged adjacent the floor of the body and forming side walls thereof, mechanisms adjacent each side wall of the body for controlling the movements of the doors when the body is in normal position and when tilting toward either side of the underframe, each said mechanism including a cam shaped member pivotally mounted on the body adjacent each door and forming part of a compression lock between the door and body, a link connection between said cams on opposite sides of the body and means on the underframe engaging at least one of said connected cam members when the body moves relative to the underframe in dumping.

13. In a dump vehicle, in combination, an underframe, a body supported thereon and tilting toward opposite sides thereof, doors forming opposite side walls of the body and hinged adjacent the floor thereof, an arm on each door depending below said hinge connection, a link adjacent each side of the body, a lever connecting each link and the adjacent door arm, a cam associated with each said link and lever connection, a link connection between opposite cams, each said cam, link and lever forming a compression lock between the associated door and adjacent side of the body for maintaining the door closed when the body is in normal position, and means on the underframe selectively engaging one of said cams as the body moves in dumping to release the lock of the door at the dumping side of the body.

14. In a dump vehicle, in combination, an underframe, a body supported thereon for tilting to opposite sides thereof, doors forming opposite side walls of the body and hinged adjacent the floor thereof, an arm on each door depending below said hinge connection, a jointed connection between each said door arm and the body, a cam rotatably mounted on the body adjacent the joint of each said jointed connection, a bearing engagement between each cam and adjacent jointed connection, each cam having a bearing face normally in engagement with said jointed connection which prevents breaking of the joint of said connection when the body is in normal position and when the side of the body at which the cam is mounted is out of engagement with the underframe, and a second bearing face which engages the underframe to control the upward breaking of said jointed connection when the body tilts about the adjacent side of the underframe and a connection between opposite cams for controlling rotation of said cams through movement of the body relative to the underframe.

15. In a dump vehicle, a lading carrying body tiltable to either side of the vehicle, opposite body side walls formed of doors hinged adjacent the floor and opening outward upon tilting of the body, an arm on each door depending below the hinge connection between door and body, a compression lock between each door arm and the adjacent portion of the body, each said compression lock being supported wholly by the body and door when in locked position, a link connection between said locks on opposite sides of the ve-

hicle, and means below the body and separate therefrom for selective engagement by said compression locks for automatically acting through said link connection to release the door at the dumping side of the body for opening when the body is tilted.

5 16. In a dump vehicle provided with an under-frame and a tilting body having opposite side walls hinged adjacent the floor thereof, the combination of a link on the body adjacent each door, a lever connecting said link and the adjacent door, a cam-shaped member pivotally mounted on the body adjacent each link, and means operably connecting said cam-shaped members and the vehicle underframe to selectively move each cam-shaped member relative to the body upon relative movement between the body and underframe so as to dispose the cam in the path of movement of the adjacent link and lever connection between the body and door to control the opening and closing movements of the door as the body moves in dumping about the adjacent side of the underframe.

10 17. In a dump vehicle in combination, an underframe, a body supported thereon and tiltable toward a side thereof, a door forming a side wall of the body and hinged adjacent the floor thereof for opening outward and downward as the body is tilted, a link and lever connection between said door and body and disposed below the plane of the floor of the body, a cam pivotally mounted on the body adjacent said link and lever connection, means on said connection engaging a face of said cam for maintaining the door in closed position when the body is in normal position, and means operably connecting said cam and underframe to move the cam relative to the body to control the opening and force the closing of the open door as the body moves the cam relative to the underframe during the tilting and righting movements of the body.

15 18. In a dump vehicle provided with an under-frame and a tiltable body having opposite side walls hinged adjacent the floor thereof, the combination of an arm on each door depending below said hinge connection, a link on said body adjacent each door, a lever pivoted to each said door arm and pivotally connected to the adjacent link, and a cam pivoted to the body adjacent each door, a link connection between opposite cams, means on each door lever engaging the adjacent cam to retain the associated door in closed position when the body is in normal upright position and means on said underframe adjacent each cam for selective engagement therewith to con-

trol the opening and closing of the associated door as the body tilts in dumping.

19. In a dump vehicle provided with an under-frame, a body mounted thereon for tilting to opposite sides thereof and doors forming opposite side walls of the body and hinged adjacent the floor thereof, the combination of a link and lever connection between each door and an adjacent portion of the body below the floor of the body, a cam-shaped member mounted on the body 10 beneath the floor thereof and adjacent each door, means on each said door lever for engagement with said adjacent cam as the door in opening moves the lever inwardly of the body and means operably connecting the opposite cams and the underframe to selectively actuate each cam by relative movement between the body and under-frame to dispose each cam in the path of movement of the adjacent door lever to control the opening and closing movements of the respective 20 doors as the body moves in dumping.

20. In a dump vehicle provided with an under-frame, a body supported thereon and tiltable about opposite sides thereof in dumping, doors forming opposite side walls of the body and 25 hinged adjacent the floor thereof, the combination in a door controlling mechanism for each door of a cam pivotally mounted on the body adjacent each door, a link connection between opposite cams, means on the underframe adjacent 30 each cam for selective engagement therewith to rotate the cam at the dumping side of the body in a direction opposite to that of the body as the body moves relative to the underframe in dumping; and means pivotally connected to each 35 door and an adjacent side of the body for movement with the door as the latter moves in opening and closing and including a portion engaging with the adjacent cam to control said movements of the door.

21. In a dump vehicle provided with an under-frame, a body supported thereon in stable equilibrium when the body is in normal upright position and selectively tilting to opposite sides thereof, and doors hinged adjacent the floor of the body to form opposite side walls of the body, the combination of a mechanism adjacent each door and wholly supported by the body, a connection between opposite mechanisms, and means on the underframe alternately engaging with said connected mechanisms to control the opening and closing of the doors as the body is tilted and righted in dumping about either side of the underframe.

CARL W. MILLER.
